UNITED STATES PATENT OFFICE.

JOSEPH GILL, OF SUMMER BRIDGE, DACRE, ENGLAND.

MACHINERY FOR THE MANUFACTURE OF LAID CORDS AND ROPES.

1,269,533.

Specification of Letters Patent. Patented June 11, 1918.

Application filed October 29, 1915. Serial No. 58,588.

To all whom it may concern:

Be it known that I, JOSEPH GILL, citizen of Summer Bridge, residing at Nydd View, Summer Bridge, Dacre, in the county of 5 York, England, subject of George V, King of Great Britain and Ireland, have invented certain new and useful Improvements in Machinery for the Manufacture of Laid Cords and Ropes, of which the following is 10 a specification.

This invention relates to machinery for the manufacture of "laid" cords, twine, ropes and the like: all hereinafter for the sake of brevity, referred to as cords; and its 15 object is to simplify and cheapen the construction of such machinery and at the same time to increase the rate of production, and to obtain a more perfect product.

A machine constructed according to this 20 invention comprises; the usual back spindles on which the yarn strand or thread bobbins are mounted. (For the sake of brevity these will hereinafter be referred to as simply bobbins.) Also the usual flier spindles and 25 bobbins on which the formed rope or cord is wound. Each strand is separately twisted by its back spindle, and the strands are twisted together to form the rope by the flier spindle in the usual manner.

Now according to this invention, each 30 strand as it leaves the strand bobbin passes through a tension device, which is rotated with or by its back spindle, and passes then to a reciprocated grooved or fluted cone 35 piece, usually termed the "top;" the number of grooves corresponding with the number of strands. The "top" which is not rotatable, serves to bring the strands together. Any other convenient device for bringing 40 the strands together may be used. Each strand is thus twisted between the "top" and the above mentioned tension device carried by or rotated with the strand bobbin 45 spindle. The strands which are brought together at the apex of the "top," pass together through a reciprocated gripping device situated close to the apex of the top.

The gripping device and the top are both 50 most conveniently mounted on a common sliding piece carried in suitable guides, and the sliding piece is reciprocated, from a crank or cam on a driving shaft, through levers and connecting rods suitably arranged.

55 The gripping device is situated in such

a manner, that it grips the strands just before the sliding piece commences to move forward. This forward movement pulls the strands off the bobbins on the back spindles: while the strands on the forward side of the 60 gripper and which are being twisted together to form the rope or cord, move forward toward, the flier; a corresponding length of rope or cord being wound by the flier on to the flier bobbin. 65

The grippers are opened at the commencement of the reverse movement of the sliding piece, during which movement the "top" brings a corresponding length of the strands together. The twisting of the separate 70 yarns or strands and the twisting of these together to form the rope or cord thus takes place continuously and simultaneously.

Although I do not wish to limit myself to any particular construction of the mechanism above referred to, I have found the 75 following to answer well:

The gripping device is formed of a pair of serrated jaws, one or both of which are made movable. The connecting rod or link, 80 which draws forward and pushes back the sliding piece, is not connected directly to the sliding piece, but to the movable jaw or jaws, in such a manner, that at the reversal of the movement of the connecting 85 rod at the back end of its stroke, it first closes the gripping device, before any movement of the sliding piece can take place; and similarly at the forward end of its stroke, the connecting rod first pulls the 90 gripping device open before any movement of the sliding piece can take place.

In order to insure the proper gripping of the cord before the forward movement of the sliding piece commences, an adjustable tension or brake device is arranged to act on 95 the sliding piece.

It will be evident, that as the strands are passing through the slots or slits in the "top," during the return or backward stroke, 100 the "top" brings the same length of the strands together.

The tension device for putting a suitable strain on the strands may consist of a pair of blocks, with sinuous faces dovetailing into 105 one another, and across which the strand is led. The pair of blocks are pressed together by springs, the pressure of which can be adjusted by screws and nuts. The blocks and springs are carried in a frame co-axial 110

with and driven from the back spindle, and the strand passes through the top journal of the frame, which is made hollow for the purpose.

And in order that my invention and the manner in which the same is to be performed may be more readily and clearly understood, I have annexed hereto the accompanying sheets of drawings of the parts of a machine for the manufacture of laid cords constructed according to this invention.

Figure 1 is a side elevation and Fig. 2 is a plan.

Fig. 3 is an elevation to a larger scale of the yarn or strand tension device shown in Fig. 1.

Fig. 4 is a side elevation, and Fig. 5 is a cross elevation of the reciprocated gripping device and the slide bar carrying the same and of one of the tension devices acting on the slide bar.

In all the figures, the same reference letter refers to the same or corresponding part or parts.

a indicates part of the frame-work of the machine.

b are the separate strands, led from the strand bobbins *c* through the tension devices hereinafter described and best illustrated in Fig. 3, which are carried by the frames of the corresponding bobbins *c* and back spindles *d* carrying fliers *d*², said tension devices being rotated with said spindles.

As shown in Fig. 3, the tension device consists of a pair of tension or tightening bars *e*, provided with semi-circular or sinuous faces, between which the strand passes. One of the bars is fixed to the frame *f*, and the other movable under the pressure of springs *g*; the compression being adjustable by means of the screw *h*.

My invention however is not limited to this construction of tension device.

Each strand on leaving the tension device *T* passes up through a trumpet guide *d'* and thence horizontally to the top hereinafter described.

As shown, three strands *b* are united to form each laid cord *j*, the strands pass from the said guiding trumpets of the back spindles *d* to guiding devices preferably consisting of the fluted cone pieces *k*, or "tops," as they are usually termed. Each top is attached to a reciprocated, slide bar *l* as hereinafter set forth. In passing from the strand bobbin to the "top," each strand is twisted, and the three strands to form the cord are brought together by the "top."

The joined strands then pass between the jaws *m* and *o* of the gripping device.

The jaw *m*, which forms part of the jaw box *m'* is fixed to the upper side of the reciprocated slide bar *l*, while the other jaw

o is hinged. A short lever *p* is formed

integral with the hinged jaw *o*, and its end is connected by the connecting rod *q* with a lever *r*, fixed on a rock shaft *s*.

The shaft *s* is rocked from the driving shaft *t* by means of the lever *u*, connecting rod *v* and crank disk *w* on the end of shaft *t*. In order to be able to time and adjust the stroke of the slide bar *l*, the driving shaft *t* is driven from some convenient moving part of the machine by change gear wheels, part of which only are shown at *x*; and the levers *r* and *u* to which the ends of the connecting rods *q* and *v* are attached are formed with slots as shown.

The slide bar *l* is subjected to the pressure of springs *y*, *y'*, see Figs. 1, 4 and 5, the pressure being adjustable by means of nuts *z* on the screwed upper ends of the studs *l'*; the lower ends of the studs being screwed or bolted to the cross frame pieces *a'*, supporting the slide bars *l*.

This pressure creates a frictional resistance to the movement of the slide bar in both directions, so that the forward movements, (see the arrow in Fig. 1), of the slide bar cannot commence until the pull of the connecting rod *q* draws the hinged jaw *o*, down against the fixed jaw *m*, nipping the joined strands between them; so that when the slide bar moves forward, the strands are drawn forward at the same time. Also it will be evident, that the return or backward movement of the slide bar cannot commence until the push of the connecting rod *q* opens the hinged jaw *o*, releasing the strands, so that they do not partake of the return movement, but the "top" brings the strands together for the length of this movement.

I mount at the end of the main frame *a* the flier spindles *3* and the bobbin *2* and *105* fliers *4*, these parts being broken away in Fig. 1 so that only the upper part of the bobbin and the upper part of the flier appear. There is no novelty in the construction and operation of these parts, so they *110* have been shown diagrammatically rather than elaborately illustrated in all details.

It will be evident that, the manner in which the laid cord is formed by a machine constructed according to this invention is *115* similar to that effected in a rope walk, except that instead of the strands being pulled out at once the full length of the walk, this is effected by a succession of intermittent short pulls alternate with the joining action *120* of the "top"; whereby greater uniformity and regularity in the manufactured cord are obtained. Also the adjustable tension devices and the means for adjusting and timing the strokes of the reciprocated slide piece *125* enable the different operations to be effected in the most efficient manner for the production of laid cords having any desired qualities or character.

Having now particularly described and *130*

ascertained the nature of my said invention, and in what manner the same is to be performed, I declare that what I claim is:—

1. A cord-making and rope-making machine, in combination with a plurality of rotating bobbins, each supplying a thread, a guiding device through which these threads are directed collectively, a gripping device for the laid cord issuing through said guiding device, means for automatically reciprocating said guiding device and gripping device and for closing and opening said gripping device at the beginning of its forward movement and of its rearward movement respectively, and rotating twisting and take-up elements for twisting the threads together and taking up the united cord.

2. In a cord-making machine, in combination with a plurality of rotating bobbins, each supplying a thread, a guiding device through which these threads are directed collectively, a gripping device for the laid cord issuing through said guiding device, means for automatically reciprocating said guiding device and gripping device and for closing and opening said gripping device at the beginning of its forward movement and of its rearward movement respectively, and rotating flier spindles and bobbins for twisting the threads together and taking up the united cord.

3. In a cord-making and rope-making machine, in combination with a plurality of bobbins, each supplying a thread, tension devices turning with each of said bobbins and acting on each of said threads respectively, a guiding device through which these threads pass collectively, a gripping device receiving the laid cord from said guiding device, a slide carrying said guiding device and gripping device, means for automatically reciprocating said slide and closing and opening said gripping device at the beginning of its forward and its rearward movement respectively, and rotating flier spindles and bobbins for twisting the threads together and taking up the united cord.

4. In a cord-making or rope-making machine, in combination with a plurality of bobbins, each supplying a thread, and ten-

sion devices therefor, a guiding device through which the threads pass collectively, forming one cord, a gripping device for the laid cord issuing from said guiding device, a slide on which said guiding device and gripping device are mounted, means for reciprocating said slide and for closing and opening said gripping device at the beginning of the forward and rearward movement of said slide respectively, and rotating flier spindles and bobbins for twisting the threads together and taking up the united cord.

5. In a cord-making or rope-making machine, in combination with a plurality of bobbins, each supplying a thread, a guiding device through which these threads pass collectively, forming one cord, a gripping device which receives the laid cord from said guiding device, a slide on which said guiding device and gripping device are mounted, means for reciprocating said slide and for closing and opening said gripping devices at the beginning of said forward movement and said rearward movement respectively, frictional devices resisting the movement of said slide and rotating flier spindles and bobbins for twisting the threads together and taking up the united cord.

6. In a cord-making or rope-making machine, a plurality of bobbins, each supplying a thread, a guiding device through which said threads pass collectively as one cord, a gripping device for this laid cord comprising a fixed jaw and a movable jaw, a slide on which said guiding device and gripping device are mounted, connections from said movable jaw to an operative part of the machine whereby said slide is reciprocated and said gripping device is closed and opened, and rotating flier spindles and bobbins for twisting the threads together and taking up the united cord.

In testimony whereof, I have signed my name to this specification in the presence of two subscribing witnesses.

JOSEPH GILL.
